UNITED STATES PATENT OFFICE.

JOHN TOWLE, OF CHICAGO, ILLINOIS.

ORNAMENTAL ELECTRIC LIGHT.

Application filed May 31, 1924. Serial No. 716,862.

To all whom it may concern:

Be it known that I, JOHN TOWLE, a citizen of the United States, and a resident of the city of Chicago, county of Cook, and State of Illinois, have invented certain new and useful Improvements in Ornamental Electric Lights, of which the following is a specification.

My invention relates to ornamental electric lights, and has for an object the provision of a light of this type which is adapted for supporting a wreath, especially a Christmas wreath, or similar decorative means; and another object is to provide such a light having words or a legend placed thereon, in the form of greetings of the season, and which light is arranged to illuminate said words or legend as well as the wreath supported on the light.

Other objects will appear hereinafter.

The invention consists in the combinations and arrangements of parts hereinafter described and claimed.

The invention will be best understood by reference to the accompanying drawings forming a part of this specification, and in which

Fig. 1 is a front elevation of my invention, with the wreath indicated thereon;

Fig. 2 is a vertical sectional view thereof;

Fig. 3 is a rear elevation of the light, without the wreath attached thereto, and

Fig. 4 is an enlarged perspective view of the spacing member.

The preferred form of construction illustrated in the drawing comprises a frame including a rear plate or disk 5 and a front plate or disk 6 substantially parallel thereto and spaced therefrom by means of spacing members or posts 7 having portions 8 bent transversely therefrom and disposed between said plates, and having their ends 9 bent over to retain the plates in position.

A socket 10 is mounted in plate 5 and supports an electric light 11 between said members 5 and 6, and is provided with an electric conductor 12 having a plug 13 for attachment to a suitable light socket. The inner wall of plate 5 is smooth and bright

to effectively reflect the rays of light from the electric light 11. An opening 14 is cut out in the front plate 6 and is arranged in the form of an ornamental design, preferably in the form of a star, and a transparent member or sheet 15 is mounted across said

opening on the inner side of plate 6 and is preferably provided in the form of a suitable sheet which will permit a legend or greeting words to be inscribed thereon. This sheet or member 13 may also be provided blank to permit the purchaser to attach his own particular legend or greeting thereon in whatever form he desires, and a plurality of such sheets may also be furnished, each sheet having a different legend or greeting neatly inscribed thereon and appropriate for the different seasons. This sheet 15 is held in position by spacing members 7, the ends 9 of said members passing through openings in said sheet.

Means is provided on my device for supporting a wreath 16, such as a Christmas wreath or other suitable ornamentation, in position thereon; such means preferably including one or more wires 17 which have their inner ends 17' passed through openings in rear plate 5 and are bent over and clamped in position thereon, and which have their outer portions curved over toward the front plate 6 so as to support a wreath in position around the outer edges of said plates 5 and 6 and between said plates and wires, as best indicated in Fig. 2 of the drawing.

The electric bulb or light 11 is positioned substantially centrally of the frame, between plates or disks 5 and 6, and is thus very effective in illuminating and setting forth the inscribed words or legend on the transparent member 15 as well as actually illuminating the wreath 16 itself; and the entire device with a suitable wreath mounted thereon thus produces a very ornamental and pleasing decoration.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A device of the class described comprising spaced members, means thereon for supporting a wreath around the edges of

- said members and partly between said members, and a light between said members for illuminating said wreath.
2. A device of the class described comprising spaced plates, and curved members extending outward therefrom for supporting a wreath between said members and the edges of said plates.
3. A device of the class described comprising a pair of spaced members, spacing means for retaining said members in position, curved wires extending outward from said members for holding a wreath between said members and said wires, and an electric light for illuminating said wreath.
4. A device of the class described comprising a pair of plates, angular spacing posts having ends fastened through said plates for retaining them in position, and means extending from the outer edges of said plates for supporting a wreath between said means and the edges of said plates.
5. A device of the class described comprising a pair of disks, means for retaining them in spaced position, and wires fastened with their inner ends in openings in one of said disks and extending outward therefrom for holding a wreath between said wires and the edges of said disks.
6. A device of the class described comprising spaced members, one of which has an opening, transparent means mounted across said opening, means extending outwardly from said members for supporting a wreath around the edges of said members, and a light between said members for illuminating said wreath and said transparent means.
7. A device of the class described comprising spaced members, one of said members being provided with a legend and the
- second member with a bright inner wall, curved means extending outwardly from said members for supporting a wreath around the edges thereof and partly between said members, and a light mounted on said second member for illuminating said legend and said wreath.
8. A device of the class described comprising a pair of spaced plates, the front plate being opaque and having an opening cut at its center to form a design, a transparent sheet with a legend mounted across said opening, spacing means for retaining said plates in position, curved members extending outwardly from said plates to hold a wreath between said members and the edges of said plates, and a socket mounted in one of said plates and provided with an electric light for illuminating said wreath and said transparent sheet and legend.
9. An ornamental electric light comprising a pair of metal disks, the rear disk having a bright inner surface and the front disk having an opening cut at its center, a transparent sheet with a legend mounted across said opening, spacing posts fastened with their ends on said disks for retaining them in parallel position, wires mounted with their inner ends in one of said disks and having their outer portions curved toward the other of said disks for retaining a wreath in position between said wires and the edges of said disks, a socket mounted in one of said disks, and a light mounted in said socket between said disks for illuminating said transparent sheet and said wreath.
- In testimony whereof I have signed my name to this specification.

JOHN TOWLE.
